CONTAINER

Robert J. Hutt and George A. Hutt,
Brooklyn, N. Y.

Application December 12, 1935, Serial No. 54,018

8 Claims. (Cl. 206—44)

This invention relates to containers or envelopes of the display type having certain economical features which will appeal to the trade, an object being to present certain novel features of construction with consequent cuts in cost of production.

Many grades of paper, appropriate for constructing display containers, are far cheaper than "Cellophane" well known as tough transparent sheet material now generally used as the window side of hermetically sealed dust-proof containers for flat or substantially flat piles, stacks or folded articles of manufacture.

The principal feature of this invention is making or forming containers having the above characteristics, in which a main or base sheet of paper cut with a base portion and an extended flap or cover portion of the same width, folded back onto the base portion at a point to determine the size or area of the package desired. This flap or cover portion may be of such size as to extend over the base portion from about $\frac{1}{4}$ to about $\frac{1}{2}$ of its dimension, so that a primary pocket portion is formed by the opaque base sheet and its extension and a secondary pocket portion covered by a sheet of "Cellophane" is formed for the content of the container, said sheet of "Cellophane" being cut to a size equal in width to the base paper portion, plus about half inch in the direction of the flap; this half inch extension of the "Cellophane" is intended to underlie the inner edge of the flap and be sealed thereto in the general single movement for sealing the three side edges of the container over the contents of the package, thus one edge of the container is self-sealed by the turned back paper flap.

Of course, the inner edge of the "Cellophane" may be sealed to the upper or outer edge surface of the flap if desired and the overlapped sealed joint may be but $\frac{1}{4}$ of an inch more or less if found sufficient for creating an air-tight union of stability.

With the above construction the buyer by grasping the double or two ply paper side of the container from $\frac{1}{2}$ to more than $\frac{3}{4}$ of the content may be inspected through the transparent window, which in practice, is quite satisfactory, and this two-ply paper construction serves also to stiffen or reinforce that side of the package far better than would a superposed sheet of paper not directly a portion of the base paper sheet, for gripping or handling the package, without damage to its contents.

In the drawing showing a preferred form of the invention,

Fig. 1 is a front or face view of the improved container and disclosing diagrammatically, its content:

Fig. 2 is a vertical section of the container as shown in Fig. 1, the line of section being indicated by the broken line 2—2 thereon;

Fig. 3 is a cross-section through the container on the broken line 3—3 of Fig. 1;

Fig. 4 is a similar view, but taken on the broken line 4—4 of Fig. 1;

Fig. 5 is a fragmentary section of the lower part of the container as here disclosed, showing the connection between the flap and the transparent sheet as a slip or unsealed joint;

Fig. 6 is a fragmentary face view and shows a separate sheet of paper as a substitute for the flap which is sealed to the transparent sheet and three edges of the base sheet;

Fig. 7 is a detail section on the line 7—7 of Fig. 6; and

Fig. 8 is a similar detail section of a form of construction in which the bottom and sides of the separate sheet of paper is sealed to three edges of the base sheet but having an unsealed or slip joint with the transparent paper sheet above described.

Referring to the drawing in detail, 10 designates the container, comprising a relatively heavy or stiff opaque base-sheet 11, which is extended in one direction for providing a flap 12 to be turned back over a portion of the content, as at 12a.

The base sheet 11, and its flap portion 12, collectively form a partial pocket 13, (see Fig. 2) while the remainder of the pocket is formed by a sheet 14 of transparent paper, which is secured at three of its edges as at 15, to three corresponding edges of the base sheet 11, by glue or otherwise, and by its fourth or inner edge 16, to the inner edge 17 of the flap 13, by glue or otherwise, thus completing the container pocket 13 for enveloping its content 18, shown here as fancy paper doilies, but of course, the utility of the invention extends to all flat goods where air and dust-proof packing for protecting goods of a delicate nature against shop-wear and damage are used.

In Fig. 4 of the drawing, the sides 19 of the flap 14, are shown as directly sealed at 20 to the base sheet 11, thus a complete pocket is formed of connected opaque and transparent sheets and proportioned so that a prospective customer may gain full knowledge of the content with respect 55

to lace designs, colors etc. disposed within the package and from the observations the selections may be made.

In Fig. 5 the joint between the flap 12 and transparent sheet 14 may be left unsealed in a slip joint 21.

In Fig. 6, a form is proposed, in which a separate sheet 22 of substantial or stiff opaque paper is substituted for the flap 12, and is sealed to the transparent sheet 14 at 23, and to the sides and an end of the base sheet 11, as at 24, and 25.

Fig. 7 better shows the sealed joint 26 forming a union between the separate piece of paper 22 and the base sheet 11.

Fig. 8 discloses another proposed form in which the separate sheet 22, has a loose or sliding connection 24 with the transparent sheet 14.

The flap portion 12 performs three functions: 1st, its overlapped attachment to the side edges produces a stiffened reinforced area to be grasped by the inspector; 2nd the bend 12a forms a blind seal at one side of the container and 3rd, and most important, is the saving of much "Cellophane" material on each container, since it has only to extend over the side seams and over the contents to underlap the inner edge of the flap portion 12 to which it may be sealed, so that in a run of say five thousand containers through the assembling machine a great saving in "Cellophane" is achieved.

Having thus described our invention what we claim is:

1. A container comprising a base sheet of substantial heavy paper having a length somewhat greater than its width, the excess material in the length of the base sheet being folded back to form a single blind sealing edge of a pocket and a single flap extending over the base sheet; a transparent sheet of material arranged over the base sheet and having a major edge portion thereof sealed to the base sheet in face to face relation and a minor edge portion sealed to a free edge of said flap and the remaining free edges of said flap being sealed to the side edges of the base sheet in face to face relation to complete the sealed pocket.

2. A container comprising a base sheet of the proper width but longer than a desired package, the excess length of base sheet material being sharply folded over the contents and base sheet; a transparent sheet of material coinciding in width to the width of the base sheet and having a length extending from the free end of the base sheet beyond to and slightly under the free edge of said folded over portion of the base sheet and the edges of the said sheets being sealed together in face to face relation to form a sealed pocket.

3. A container for flat articles comprising an opaque base sheet, a strip of opaque material co-extensive in width to that of said base sheet

and extending from the bottom edge thereof, said strip overlying a substantial portion of said base sheet and having its side edges connected in face to face relation to like edge portions of said base sheet, a sheet of transparent material having a width co-extensive with that of said base sheet and having its top and side edges connected to like edge portions of said base sheet in face to face relation thereto, and the lower edge of said transparent sheet slightly overlapping the upper edge of said strip.

4. A container for flat articles comprising an opaque base sheet, a strip of opaque material extending from the bottom edge of said base to overlie a substantial portion thereof and having its side edges connected in face to face relation with like edges of said base, a sheet of transparent material overlying the exposed portions of said base and having its top and side edges connected to like edges of said base in face to face relation thereto, the lower edge of said transparent sheet slightly overlapping the upper edge of said strip, and at least the top and side edges of said transparent sheet and said strip terminating at like edges of said base sheet.

5. A container comprising a base sheet, a single portion thereof being adapted to be folded back upon itself to overlie a substantial portion of said base sheet, the side edges of said portion terminating at like edge portions of said base sheet and being attached thereto in face to face relation, a transparent sheet overlying the remainder of said base sheet, one edge of said transparent sheet having a slightly overlapping relation with the free edge of said folded portion, the remaining edges of said transparent sheet terminating at like edge portions of said base sheet and being attached thereto in face to face relation.

6. The structure of claim 5, and the overlapping edges of said transparent sheet and said folded portion being joined together in face to face relation.

7. A container comprising a flat flexible base, a second flat flexible member overlying a substantial portion of said base and having its side and bottom edges attached to like edges of said base to form an open pocket to receive the container contents, and a flat flexible transparent member overlying the remainder of said base and contents, the lower edge of said transparent member having a slightly overlapping relation with the free edge of said pocket, and the side and top edges of said transparent member being attached to like edge portions of said base in face to face relation.

8. The structure of claim 7, and the overlapping edges of said transparent member and said pocket being attached together.
